UNITED STATES PATENT OFFICE

155,739

DESIGN FOR A PUMP

John D. Shafer and George B. Shafer, Dayton,
Ohio, assignors to U. S. Lite-Ray Company,
Dayton, Ohio, a corporation of Ohio

Application October 21, 1947, Serial No. 142,070

Term of patent 7 years

(Cl. D65—1)

To all whom it may concern:

Be it known that we, John D. Shafer and George B. Shafer, both citizens of the United States of America, both residing at Dayton, in the county of Montgomery and State of Ohio, have invented a new, original, and ornamental Design for Pump, of which the following is a specification, reference being had to the accompanying drawing, forming a part thereof.

Fig. 1 is a view in perspective of a pump, embodying our new design; and

Figs. 2 and 3 are views of the pump in front elevation and top plan, respectively, and on a smaller scale.

The dominant features of the design for the pump disclosed reside in the domed cap, the enclosed wall thereunder and the spout extending

outwardly therefrom, all having the configurations as shown.

We claim:

The ornamental design for a pump, substantially as shown and described.

JOHN D. SHAFER.
GEORGE B. SHAFER.
